UNITED STATES PATENT OFFICE

GEORGE J. FLANAGAN, OF CHICAGO, ILLINOIS; EARLE C. GRANNAN EXECUTOR OF SAID
GEORGE J. FLANAGAN

BOOKHOLDER

Application filed October 30, 1930. Serial No. 492,144.

This invention relates in general to a book holder and in particular is directed to improvements in means for supporting large and heavy reference volumes, wherein the binding of the book is protected when the book is not in use, and which is easily operable to permit the book to be opened for perusal.

Heretofore devices for holding and supporting heavy reference volumes have in the main consisted of a vertically adjustable standard having a tiltable head at its upper end and a set screw for securing said head in adjusted position. A commonly constructed this head included a pair of laterally adjustable brackets, each of said brackets having hingedly secured thereto a wing member for engagement with one of the cover members of the book, and a stationary cradle mounted between and independently of said wings for engagement with the back of the book to assist in supporting it between the two wing members. In these devices manually operable latching means were provided for latching the wings either in a substantially vertical position or in an extended position for supporting the book in a position for perusal.

These devices were objectionable in that the set screw was unsatisfactory for securing the tiltable head in adjusted position, since it could not be tightened sufficiently without the use of a wrench or other tool which was not as a rule conveniently obtainable. For this reason, the set screw was often times not tightened, the result being that the head would be tilted unsuspectedly due to the weight of the reference volume and cause the book holder to upset and possibly damage the book. Another objection to the prior devices as described above, was that the cradle for engagement with the back of the book was rigidly mounted between the wing members. Therefore, as the wings were moved from the closed to open position, the back of the book would be moved out of engagement with the cradle and there would be relative movement between the book cover members and the wing members. In due time this movement would wear out the binding of the

book cover members. These devices were further objectionable in that the manually operable latching means for latching the wings in either the closed or open positions were very inconvenient to operate.

To overcome these and other objections to prior art devices, it is an object of this invention to provide an improved book holder that is constructed from stamped metal parts, that is economical to manufacture, pleasing in appearance, and convenient to operate.

A further object of this invention is to provide a book holder having improved means for adjusting the angle at which the book will be supported.

It is a further object of this invention to provide a book holder of the type having wings which may be moved to a plurality of positions for supporting a book when it is either opened or closed, and improved means for automatically latching said wings in each of said positions.

It is a further object of this invention to provide a book holder having an improved support for engagement with the back of the supported book, which is adapted to conform to the curvature of the said back regardless of the thickness of the book, and which is so mounted that it will follow the movement of the back of the book during the change of the wing members from closed to open position and vice versa.

Another object of this invention is to provide an improved book holder in which the wing members are mounted in such a manner that there will be no relative movement between the book cover members and the wing members, when the wings are moved from open to closed position and vice versa.

It is also an object of this invention to provide a book holder having improved means for adjusting the spacing between the wing members to accommodate books of various thickness.

In accordance with the general features of this invention, I provide improved means for adjusting the angle at which the book will be supported, said means comprising a hinge joint or knuckle having a plurality of

100

friction discs, associated therewith which are held in cooperative relationship by a simple clamping device. Each of the wing supporting brackets is provided with a pair of spaced slide members which are engaged between a pair of clamping members, one of said slide members being spaced on one side of the connection of the tiltable head to the hinge joint and the other of said slides being spaced on the other side of said connection member. This construction more efficiently secures the wing supporting brackets against the torsional forces as a result of supporting the heavy book in an overhung position. Further, instead of providing a stationary support for engagement with the back of the book, I provide a flexible support of lazy-tong construction which is connected between the lower edges of the wing members and curved to fit the back of a book. With this construction, the support will accommodate itself automatically to the space between the lower edges of the wing members when they are moved from one position to another, and will also follow the movement of the back of the book so as to support it at all times. Furthermore, resilient means in the form of a leaf spring is provided on each of the wing members for cooperation with a pin in such a manner that when the associated wing member is moved from a substantially vertical position to a substantially horizontal position, the spring will pass through a dead center position and will automatically latch the wing in either position to which it is moved.

Other and further important objects of this invention will be apparent from the disclosures in the accompanying drawings and the following specification.

The invention (in a preferred form) is illustrated on the drawings and hereinafter more fully described.

On the drawings:

Figure 1 is a front view of a book holder embodying the features of my invention, which shows the wing members in open position for supporting a book for perusal.

Figure 2 is an enlarged fragmentary side view of the head, showing the wings in closed position, means for laterally adjusting the wings to accommodate books of different thickness, and means for adjusting the angle at which the head will be supported.

Figure 3 is an enlarged fragmentary perspective view showing the relationship of the wing supporting brackets, and the instrumentalities for adjusting the space between said brackets.

Figure 4 is a sectional view through the swivel joint connection between the supporting standard and the head, taken substantially on line IV—IV of Figure 2.

Figure 5 is a plan view of the head adjusting means as viewed from below.

Figure 6 is a rear view of my improved book holder showing the operative relationship of the various elements therein, and having cut away portions showing means for automatically latching the wing members in either the open or closed position.

Figure 7 is an enlarged view showing the details of one of the movable friction discs.

Figure 8 is an enlarged fragmental view of the hinge joint or knuckle connecting the head and standard having cut away portions to show the relationship between the movable friction discs and the stationary friction discs.

As shown on the drawings:

In the illustrated embodiment of my invention, there is shown in Figure 1 a base or supporting structure A for my improved book holder. This base comprises a tubular standard 1 which is provided at its lower end with a plurality of equally spaced legs 2, each of which is provided with a glider foot or caster 3 which permits my improved book holder to be moved easily from one place to another. Although I have not endeavored to show the specific manner in which the legs 2 are connected to the standard 1, it is contemplated that the legs may be connected to the standard in any conventional manner which will permit the standard to be longitudinally adjusted to vary the height at which the head of my device will be supported. An auxiliary book shelf 4 is carried by the standard so as to rest on the top of the legs 2. I have found it to be desirable in some cases to construct this auxiliary book shelf of heavy material in order to effect a low center of gravity in my device, thereby increasing the stability thereof.

The book holding head B is swiveled at the upper end of the standard 1 by providing a pair of semi-tubular members 5 and 6 which are secured together by an encircling collar 7 in confronting relationship to form a tubular portion adapted for rotation within the standard 1. The collar 7 obviously will abut the upper end of the standard and limit the distance that the members 5 and 6 will extend thereinto.

A joint or knuckle C hingedly supports the head B of my device so that it may be adjusted or tilted to vary the angle at which it is desired to support the book. The stationary portion of this joint is formed by the members 5 and 6, which are each cupped at the upper end as shown at 8, and provided with a central aperture 9 for receiving therethrough a hinge and clamping bolt 10. This bolt is threaded on one end for receiving a wing nut 11, said bolt and wing nut cooperating to clampingly engage the outer surfaces of the members 5 and 6. In

order to prevent the bolt 10 from turning when the wing nut 11 is tightened or loosened, the aperture 9 in the cupped portion of the member 6 is shaped to receive 5 a square shoulder on the head of the bolt. The rims of the cupped portions 8 of the members 5 and 6 are outwardly deflected to form flanges 12 which are in confronting and spaced relationship. These flanges are 10 provided with cut out portions 13 which are in alignment and serve a purpose which will appear subsequently. The movable portion of the joint is formed by a pair of discs 14 which are disposed between the flanges 12 which are 15 disposed between the flanges 12 and held in spaced relationship by a washer 15 which surrounds the shank of the bolt 10. The discs 14 are each provided with a central aperture 16 for receiving the shank of the bolt 10 therethrough for supporting 20 the discs 14 for turning movement. Each of the discs 14 is provided with a lip 17 which extends outwardly into one of the cut out portions 13 for limiting the movement of the discs 14 relative to the flanges 25 12. Intermediate points of adjustment between the limits of rotation as established by the coaction of the lips 17 and the ends of the cut out portions 13 are provided by forming a plurality of recesses 18 in the 30 outer surface of the disc 14 which engages the inner surface of the flange 12 on the member 5. A projection 19 is formed on the inner surface of this flange for successive registration with the recesses 18. Each 35 of the discs 14 is provided with a radially extending arm which terminates in an outwardly extending portion 20 which is at right angles to the plane of the disc. These arms form a support for a clamping plate 40 21 which is spot welded or otherwise secured thereto.

The clamping plate 21 is rectangular in form and is provided with lateral channel portions 22 and 23 which extend longitudinally thereof. A similarly formed clamping plate 24 is disposed above the clamping plate 23 and provided with an extruded portion 25 in each of the lateral channels thereof which defines an aperture having its inner surface threaded for receiving the threaded end of a thumb screw 26 which extends through an aligned aperture formed in the confronting channel portion of the plate 21. Since the clamping plates 21 and 50 24 are in confronting relationship, their corresponding channel portions will cooperate to form a pair of guideways which are oppositely spaced on each side of the longitudinal center line of the clamping plates. 55

60 A pair of interfitting channel shaped slide bars 27 and 28 are arranged for longitudinal movement in each of the guideways so formed, an end of the bar 27 projecting from one end of the guideway and an end of the bar 28 projecting from the opposite

end thereof. The bars 27 and 28 in each guideway are respectively provided with longitudinally extending apertures 29 and 30 for receiving the shank of the thumb screw 26 therethrough for limiting the 70 movement of the bars through the guideway. This arrangement permits the bars to be adjusted so that their outer ends will project a greater or less amount from the ends of the guideway as desired, and by tightening the thumb screw 26 the bars may be 75 clamped between the plates 21 and 24 and thereby secured against movement from the adjusted position.

The bars 27 are connected together at 80 their outer ends for unit adjustment by spot-welding or otherwise securing a plate member 31 thereto. The outer ends of the bars 28 are similarly connected together by a plate member 31. Each plate member 31 is formed to have an upwardly extending integral portion 32 having its lateral margins bent inwardly to form a channel shaped bracket having side walls 33 which are secured at their lower ends to lugs 34 on the 85 plate member 31.

The upper ends of the side walls 33 are shaped to form a pair of spaced lugs 35 which project above the upper edges of the portion 32, said lugs being provided with aligned apertures for receiving a hinge pin 36 which extends therebetween. A wing member 37 is hinged on the pin 36 by means of spaced lugs 38 formed on the wing member and having aligned apertures through 100 which the hinge pin passes. A strap 39 of spring material, which is secured by rivets 40 to the wing member, is provided with an angularly deflected portion 41 which extends between the side walls 33 where its free end 105 engages a pin 42 which extends between said side walls in a direction parallel to the hinge pin 36. An end edge of the wing 37 is deflected inwardly at right angles to form a flange 43. The construction just described 110 permits the wing 37 to be rotated either to a substantially vertical position as shown in Figure 6 or a substantially horizontal position as shown in dotted lines therein. In either position the free end of the spring strap 39 and the pin 42 cooperate to automatically latch the wing in place. It will be noted that as the free end of the spring strap 39 is moved around the pin 42 the 115 spring will pass through a dead center position, this action being effective to force the wing in one direction before reaching the dead center position and in the opposite direction after passing through said position.

The back 43' of a book which is shown in dotted lines in Figure 6 is supported by a cradle D which extends between and is connected to the lower edges of the wing members 37-37 by means of clips 44 which 120 125 130

tend through slots 45 of the wing members. This cradle is formed by a plurality of crossed bars 46 which are pivoted together so as to function upon the principle of lazy 5 tongs. With this construction, it will be apparent that as the wings are moved to an open or closed position the cradle will automatically be compressed or extended as the case may be, and be raised or lowered to 10 follow the movement of the supported book, whereby relative movement between the cover members 47 of the book and the wing members is prevented.

15 My invention therefore provides an improved book holder which is constructed of stamped metal parts; which is provided with improved means for adjusting the angle at which the book will be supported; which is provided with means for automatically latching the book engaging wings either in an open or closed position; which is provided with a supporting cradle for engagement with the back of the supported 20 book, which will follow the movement of the book during change of the book engaging wings from open to closed or closed to open position; a device in which the wing members are mounted so that there will be no tendency for relative movement between 25 the cover members and the book supporting wings; and improved means for laterally adjusting the spacing between the wing members to accommodate various size books.

30 I am aware that many changes may be made and numerous details of construction may be varied through a wide range without departing from the principles of this invention, and I, therefore, do not purpose limiting the patent granted hereon otherwise than as necessitated by the prior art.

35 I claim as my invention:

1. A book holder comprising a support, a stationary friction disc carried by said support having a central aperture, said disc having a cut out peripheral portion, movable means for engaging and holding a book, a friction disc carried by said means having a central aperture, said latter friction disc having a deflected portion extending into the cut-out portion of said stationary friction disc, a pivot pin extending through said apertures, and a nut cooperating with said pin for clamping said discs together.

40 2. A book holder comprising a support, a pair of complementary clamping plates defining a plurality of spaced parallel guideways, a plurality of slide members extending into and movable in said guideways, book engaging wings carried by said slide members, and means for causing said plates to clampingly engage said slide members in said guides, which means also limits the movement of the slide members, when the 45 plates are unclamped.

3. A book holder comprising a support, a

pair of complementary clamping plates connected to said support and defining a plurality of spaced guideways extending longitudinally of said plates, a plurality of spaced brackets, a plurality of spaced slide members secured to said brackets and extending into said guideways, the slide members of one bracket having slots in registration with slots on the other slide members, a wing member hinged on each of said brackets for engagement with the book, and means extending through said slots to cause said plates to frictionally engage said slide members and limit the axial movement of the slide members, when the plates are released from frictional engagement.

4. A book holder comprising a support, a pair of wings connected to said support and spaced apart to receive a book therebetween, said wings being arranged for outward movement to a substantially horizontal plane for supporting the book in an open position and towards each other to support the book in closed position, and a system of crossed bars pivotally interconnected and associated with said wings for engagement with the back of the book.

5. A book holder comprising a pair of members supported in spaced relationship for receiving a book therebetween, said members being arranged for outward movement to a substantially horizontal plane for supporting the book in a position for perusal and towards each other to support the book in closed position, and a support of 50 lazy tong construction connected between said members for engagement with the back of the book.

6. A book holder comprising a support, a pair of spaced wings hingedly connected to said support, for engaging the opposite cover members of a book, said wings being arranged for outward movement to a substantially horizontal plane for supporting the book in a position for perusal and towards each other for supporting the book in closed position, and a support connected between the lower edges of said wings of lazy tong construction for engagement with the back of the book, said support being shaped to conform to the curvature of said back.

7. A book holder comprising a support, a pair of laterally adjustable brackets connected to said support, a pair of members connected to said brackets and adapted to receive a book therebetween, and a lazy-tong structure connected between said members to engage the back of the book and support the same in any adjusted position of said brackets.

8. A book holder comprising a support, a pair of laterally adjustable brackets connected to said support, a pair of members connected to said brackets and adapted to

receive a book therebetween, each of said members being movable to a substantially vertical position and a substantially horizontal position, a lazy-tong structure connected between said members to engage the back of said book and support the same in any adjusted position of the brackets, and means for automatically latching each of said members in either position.

10 9. A book holder comprising a support, a pair of laterally adjustable brackets connected to said support, a pair of wings connected to the respective brackets for movement to open and closed positions, said 15 wings being adapted to receive a book therebetween when in the closed position, a lazy-tong structure connected between said wings to engage the back of the book and support the same in any adjusted position of the 20 brackets, the weight of the book tending to hold the wings in closed position, and spring means for latching said wings in either open or closed position, said spring means augmenting the weight of the book to 25 hold the wings in closed position.

In testimony whereof I have hereunto subscribed my name at Chicago, Cook County, Illinois.

GEORGE J. FLANAGAN.
